UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

GOLF TEE.

Application filed March 19, 1927. Serial No. 176,813.

My invention relates to golf tees. It is the object of my invention to provide a golf tee consisting of a plurality of relatively long golf ball supporting members 5 mounted on a base having a relatively broad bearing surface, and a relatively sharp narrow ground engaging portion, particularly adaptable for use in hard ground where a long pin for engaging the ground is unsuccessful and inadvisable.

Referring to the drawings:

Figure 1 is a top plan view of the tee;

Figure 2 is a side elevation thereof;

Figure 3 is an elevation of the tee with the 15 ball in position, the tee being shown in section along the line 3—3 of Figure 1 looking in the direction of the arrows.

Referring to the drawings in detail, 1 designates an upstanding golf ball supporting 20 arm preferably square in section located on a corner of the relatively flat body 2. The point 3 of this arm supports a golf ball 4. The base of the body 5 is provided with a relatively narrow, relatively short, ground 25 engaging needle or pin 6.

The arms 1 are much deeper than the depth of the body 2 or the depth of the pin 6, while the bearing surface of the body 5 is sufficient in combination with the pin 6 to 30 prevent the tee from tilting.

In dry weather when the course is hard, this type of tee is particularly adaptable as it gets the ball up above the ground at the desired elevation, the tee is easy to insert in the hard ground and therefore the condition 35 of the course does not make it difficult or impossible to insert the tees which have longer and larger ground engaging shanks.

It will be understood that I desire to comprehend within my invention such modifications as may be necessary to adapt it to varying conditions and uses.

Having thus fully described my invention, what I claim as new and desire to secure by Letters Patent, is:

In a golf tee, a flat base, a plurality of relatively long up-standing golf ball supporting fingers angular in section, the upper edges of which are adapted to support the golf ball in such a manner that the golf ball is supported on a plurality of separated points, such points being located at the corners of the up-standing members where the side walls join the top thereof, and a flat ground engaging member adapted to prevent 50 rotation of the tee.

In testimony whereof, I affix my signature.

GEORGE CLAUSING.
